(57) **CLAIM**

The ornamental design for a combined bag recycler and holder, as shown and described.

DESCRIPTION

FIG. 1 is a perspective view of the present combined bag recycler and holder showing my new design;

FIG. 2 is another perspective view thereof;

FIG. 3 is a front view thereof;

FIG. 4 is a side view thereof, the other side being a mirror image thereof;

FIG. 5 is a top plan view thereof;

FIG. 6 is a bottom plan view thereof; and,

FIG. 7 is a rear view thereof.

The broken line showing of a cabinet and bag in FIG. 1 is included for the purpose of illustrating environment and forms no part of the claimed design.
